UNITED STATES PATENT OFFICE.

LEON A. GRIGSBY, OF LOUISVILLE, KENTUCKY, ASSIGNOR TO LOGAN CO., INC., OF LOUISVILLE, KENTUCKY, A CORPORATION OF KENTUCKY.

ORNAMENTAL PROTECTING GRILLE.

Application filed August 4, 1927. Serial No. 210,636.

This invention relates to protecting devices and more particularly to an ornamental protecting grille for screen doors and similar structures.

5 An important object of the invention is to provide a novel grille formed of interwoven strips of metal having novel means for adjusting it to doors and similar structures of varying widths.

10 A further object is to provide a novel ornamental grille which may be made in standard sizes and provided at its upper and lower ends with adjusting arms to permit it to be secured to the frame portions of screen doors 15 and similar structures.

15 A further object is to provide a novel ornamental grille including interwoven vertical and horizontal strips, and to provide adjusting arms extending horizontally from 20 the corners of the grille and provided with inturned lips at their inner ends adapted to be arranged in openings formed in the upper and lower horizontal strips of the grille, the outermost vertical strips being turned inwardly to provide slots or sockets in which the adjusting arms are arranged.

25 Other objects and advantages of the invention will become apparent during the course of the following description.

30 In the drawings I have shown one embodiment of the invention. In this showing,

Figure 1 is a side elevation of a portion of a screen door showing the device applied,

Figure 2 is a detail section on line 2—2 of 35 Figure 1, and,

Figure 3 is an enlarged fragmentary perspective view of one corner of the grille.

30 Referring to the drawings, the device has been shown applied to an ordinary screen door 10 including side frame portions 11 and wire cloth 12 of the usual type.

The device forming the subject matter of the present invention comprises a grille 13 formed of vertical and horizontal metal strips 14 and 15 respectively interwoven as shown, and having their overlapping portions spot welded or otherwise secured together. The upper ends of the vertical strips 14 may be twisted at right angles to the body 45 of the strips as at 16 and turned downwardly and inwardly as at 17 to provide the grille with an ornamental top.

50 The end portions of the uppermost and lowermost strips 15 are provided with open-

ings 18 spaced apart a suitable distance as 55 will be apparent. The extremities of the outermost vertical strips 14 are turned inwardly and downwardly as at 19 to form slots or sockets 20 for a purpose to be described. Metal adjusting arms 21 are adapted to be arranged adjacent each corner of the grille and may be provided at their outer ends with openings 22 to receive screws or other fastening elements whereby they may be secured to the frame portion of the screen 60 door or other structure. The inner end of each arm 21 is provided with a laterally extending lip or tongue 23 which is adapted to be selectively arranged in the openings 18. Intermediate its ends, each adjusting arm is 65 adapted to project through one of the slots or sockets 20 as indicated in Figure 1.

The operation of the device is as follows:

The grilles are made in a standard size according to the use to which it is to be put. 70 Each grille is furnished with a sufficient number of the adjusting arms 21. When it is desired to attach the grille to a screen door, the tongues 23 are arranged in selected openings 18 whereby the outer ends of the 75 arms will lie against the side frame portions of the screen door. The arms project through the slots 20, as previously stated. Screws or other fastening elements are then inserted through the openings 22 and secured to the door, and the grille will be securely held in position thereagainst. It will be noted that the arms provide means for securing the grilles to doors of varying widths thus eliminating the necessity of making 80 different grilles for doors of different sizes. No fastening elements are necessary for holding the arms in position on the grille, the tongues 23 and slots 20 serving to prevent movement of the arms after they are secured against the door. It will be apparent 85 that the device readily may be adjusted and attached to the usual screen door structures without the use of special tools or the necessity of breaking or shortening projecting 90 attaching arms.

95 It will be apparent that the device provides pleasing ornamentation for the screen door and protects the wire cloth from being punctured by carelessly pushing thereagainst. While the device has been illustrated as being applied to a screen door it will be apparent that it is applicable to other me- 100

chanical structures including frame members or posts to which the adjustable arms may be secured.

It is to be understood that the form of the invention herewith shown and described is to be taken as a preferred example of the same and that various changes in the shape, size and arrangement of parts may be resorted to without departing from the spirit 10 of the invention or the scope of the subjoined claims.

I claim:

1. A device of the character described comprising a body having a plurality of alined openings in opposite sides thereof, said body including vertically extending side bars, a plurality of width adjusting members for said body provided with projections at one end adapted to be received in certain of said 15 openings, and a socket carried by said body adjacent each of said adjusting members and adapted to receive said members at a point spaced from the projection thereof, said side bars being turned back upon themselves to 20 form said sockets.

2. A device of the character described comprising a body having a series of horizontally alined openings in each side adjacent the top and bottom thereof, said body including vertically extending side bars, a width adjusting member associated with each series of openings and provided with a projection adapted to be received in one of the openings thereof, and a socket carried by said body adjacent 25 each of said adjusting members and adapted to receive said members therein, the extremities of said side bars being turned back upon themselves to form said sockets.

3. A device of the character described comprising a body having a plurality of horizontally alined openings in each side thereof adjacent the top and bottom, said body including vertically extending side bars, a width adjusting bar arranged horizontally and associated with each series of openings, each of said adjusting bars being provided at its inner end with a laterally extending tongue adapted to be received in one of said 40 openings, and a socket carried by said body adjacent each of said adjusting bars and adapted to receive said adjusting bars at a point spaced from the projection thereof, the extremities of said side bars being turned 45 inwardly toward each other to form said sockets.

4. A device of the character described comprising a rectangular grille formed of interlaced vertical and horizontal strips, the uppermost and lowermost horizontal strips being provided in their end portions with a series of horizontally arranged openings extending therethrough, a width adjusting bar arranged horizontally against each end portion of each of said last named horizontal strips, each of said bars being provided at its inner end with a laterally extending lip adapted to be received in one of said openings, and a socket carried by said grille adjacent each of said adjusting bars and adapted to receive said bars at a point spaced from 60 the lip thereof, the extremities of the outermost vertical strips being turned inwardly toward each other and spaced from the body thereof to form said sockets.

In testimony whereof I affix my signature.
LEON A. GRIGSBY.
